UNITED STATES PATENT OFFICE.

MAURICE FORCOZ, OF STRATFORD, CONNECTICUT.

PACKAGE-TIE.

1,287,944.

Specification of Letters Patent.

Patented Dec. 17, 1918.

Application filed January 15, 1917. Serial No. 142,495.

To all whom it may concern:

Be it known that I, MAURICE FORCOZ, a citizen of France, residing at Stratford, in the county of Fairfield and State of Connecticut, have invented certain new and useful Improvements in Package-Ties, of which the following is a specification.

This invention relates to package ties.

One of the main objects of the invention is to provide a package tie of very simple construction and operation which will fit closely against the surface of a package so as to occupy but very little space. A further object is to provide a tie which may be produced from a continuous piece of material at very small cost. A still further object is to provide a tie having a gripping member so disposed relative to the body of the tie that the tension of the cord or tying medium may be utilized to force the gripping member into tight frictional engagement with the free portion of the cord. Further objects will appear from the detailed description.

25 In the drawings:—

Figure 1 is a top plan view of a package tie constructed in accordance with my invention is applied.

Fig. 2 is a top plan view of a blank from which the tie is formed.

Fig. 3 is a side view of the tie.

Fig. 4 is an end view.

Fig. 5 is a section on line 5—5 of Fig. 1.

Fig. 6 is a side view of a modified form 35 of tie,

Fig. 7 is a top plan view of the modified form of tie,

Fig. 8 is an end view of the same,

Fig. 9 is an end view of the same taken 40 from the end opposite to that shown in Fig. 8.

In making my tie a substantially triangular plate 1 is stamped out of sheet metal, having, at its apex, the integral laterally 45 extending tabs 2 and, at its base, a tongue 3 integrally connected to the plate by a neck 4. The plate 1 is further provided, at its transverse center and somewhat nearer its apex than its base, with an opening 5 in which is secured a cylindrical turning post 6 having a disk-like head 7. This post may be formed with the plate 1 by swaging or spinning, or may be made separate and secured through the opening 5.

55 The two tabs 2 are turned upward and inward to provide an integral cylindrical

sleeve at the apex of the plate and tongue 3 is turned inward and downward so as to occupy a position parallel with, and spaced above, the plate 1 at the base thereof. The 60 tongue 3 provides a resilient clip for securing the free end of the cord or other tying medium, the resiliency of this clip being further increased by the neck 4 which is bent into substantially arcuate shape. 65

As will be noted from Fig. 4 the tongue 3 is bent downward and inward at a slight angle to provide an inwardly converging cord receiving passage or opening. Also, the tongue is stamped to provide a central 70 longitudinally extending downwardly directed rib or gripping member 3^a of approximately V-shape in cross section. This rib is positioned directly above a V-shaped groove 3^c formed by stamping in plate 1. 75 The rib and groove coöperate to bite into and firmly grip the cord frictionally without injuring the same, the rib also acting as a reinforcing element for imparting rigidity to tongue 3. The outer end of tongue 3 is 80 turned up as at 3^b to facilitate insertion of the cord.

In using my tie, the cord 8 is provided at one end with a knot 9 which is made sufficiently large to prevent its passing through 85 the sleeve 2, after which the cord is drawn through the sleeve so as to bring the knot into contact with the inner end of the sleeve. The cord is then passed about the package longitudinally of the same, the plate or tie 90 being placed at the substantial center of the top of the package. The cord is brought back to the turning post 6 about which it is given a half turn and passed about the package transversely, as at 8^a, being brought 95 back to the turning post about which it is given one or more turns in a transverse direction to the original turn, as at 8^b. The free end portion 8^c of the cord is then passed beneath the tongue 3 so as to be tightly 100 gripped between the same and the base portion or plate 1 by rib 3^a and groove 3^c.

As will be noted from Fig. 1 of the drawings, the longitudinally extending portion of the cord remote from the apex of plate 1 105 is passed above tongue 3, as at 3^a. Due to the tension to which the cord is subjected, downward pressure will be exerted upon the tongue 3 so as to force the same downward into tight gripping engagement with the 110 end portion 8^c of the cord. By this means, in addition to the cord being gripped by the

resiliency of tongue 3 and neck 4, the tension of the tying medium itself is also utilized to insure tight gripping of the free portion of the cord. Also, the several wraps 5 pings which the cord is given about the turning post 6 will cause tight frictional engagement of the turns of the cord at this point so as to prevent working loose of the cord.

10 The modified form of tie shown in Figs. 5 to 7 is constructed similarly to, and operates in the same manner as, the tie shown and described above, except that this modified form is made from a single continuous 15 piece of wire. A piece of spring steel, or other suitable wire, is bent to form an eye 10 at one end of a longitudinally extending bar 11. The wire is then bent upward to provide a vertical arm 12, then turned downward and outward at right angles and bent 20 to form a spiral head 13, the end of the outer coil being passed beneath the inner coil, the wire then being bent downward to provide a vertical arm 14 parallel with, and 25 closely adjacent, arm 12. At the lower end of arm 14, the wire is turned upward at right angles to provide a longitudinally extending bar 15 in axial alignment with bar 11. At the outer end of bar 15 the wire is 30 turned laterally at right angles and bent to form two parallel closely adjacent rods 16 and 17 integrally connected to bar 15 by rod 18, and an upper transversely extending 35 gripping bar or tongue 19 positioned above bars 16 and 17 and midway between the same. In using this form of tie the cord is inserted through the eye 10 and passed about the turning post composed of the arms 12 and 14 and the head 13, the free portion of

the cord being inserted beneath the gripping 40 tongue 19 and above the rods 16 and 17, the longitudinally extending run or strand of the cord being passed above tongue 19 so as to force it downward into tight frictional engagement with the loose portion of 45 the cord in the same manner as tongue 3 is forced into engagement with the cord in Fig. 1 of the drawings. A package tie constructed in this manner may be quickly and 50 easily produced at very small cost by the simple expedient of bending a piece of wire in the manner described.

As will be noted, the binding post in both forms of ties is positioned at the longitudinal axis of the tie. By arranging the binding post in this manner, I insure that there will be no tendency toward lateral movement of the tie, so that it will at all times be maintained in accurate position on the package.

What I claim is:—

A package tie comprising a triangular plate, a pair of oppositely directed tongues formed integrally on its apex, bent toward each other to form a sleeve, an integrally 65 formed neck in an opposite corner of the plate, a tongue formed on said neck to extend above the plate in spaced relation thereto and parallel to the adjacent edge of the plate, and a headed turning post mounted 70 centrally of the plate.

In testimony whereof I affix my signature in presence of two witnesses.

MAURICE FORCOZ.
